SYSTEM FOR MINING A SOLUBLE

Edward N. Trump, Syracuse, N. Y.

Application August 12, 1933, Serial No. 684,801

7 Claims. (Cl. 262—3)

My invention relates to improvements in means for mining a soluble. It has been common practice for many years to mine a soluble such as salt by introducing a solvent, such as water, by means 5 of a hole drilled into the bed of rock salt and withdrawing the solution therefrom.

It has even been proposed to introduce a non-solvent, such as air, into the mine cavity to protect the roof of the cavity from the solvent, and, 10 as the cavity increases outwardly and downwardly, to introduce more air to protect the increasing dimensions of the cavity roof; this procedure being repeated from time to time until the cavity has spread out to such an extent that 15 the roof of the cavity caves in, after which the protective layer is no longer employed.

As all impurities fall to the bottom of the cavity, efficient downward dissolving is not effected, as the sediment, falling upon the bottom 20 of the cavity, interferes with the action of the water upon the salt beneath.

In accordance with the present invention, means are provided for controlling the protective layer of non-solvent, such as air, either with 25 respect to volume or pressure, in order to secure from time to time the required top level of the solvent, and this level of the solvent is changed, step by step upwardly, so that the salt may be dissolved from beneath upwardly in stages.

By starting at the bottom of the salt bed, I undercut the bed, from the bottom up, for as small a height as possible, by maintaining a layer of non-solvent, such as air, which will float on the surface of the solvent to protect the roof of 35 the cavity, until the desired diameter is secured. The required level of the solvent is maintained by introducing a surplus of air into the cavity so that there will be a continuous discharge of surplus air at a determined level, or, by controlling the pressures as hereinafter described. After the desired horizontal diameter of the cavity 40 is secured, by changing the point of discharge, or the differential pressure of the air, the level of the solvent is permitted to rise, and thus the dissolving proceeds step by step upwardly as described.

The advantages of the means for securing such procedure are as follows:—

As the salt bed is attacked gradually, step by 50 step, upwardly from below, the cavity becomes bell-shaped, that is, formed with an arched roof, so that the bed may be almost entirely dissolved before the roof breaks.

As the solution or brine naturally takes the 55 lowest position in the mine cavity, the fresh water

is always in contact with the salt in the upper part of the cavity. Hence dissolving upwardly from below is effected with maximum efficiency.

By providing means for causing a separation of the solution discharging from the mine cavity, at a point below the introduction of fresh solvent, a richer solution is secured. 5

By providing means for introducing air mixed with the water under pressure, the air is absorbed by the water as the pressure increases, and much 10 less pressure is required than when the air and water are introduced separately.

By providing means for permitting the escape of surplus air with the brine, less pressure of introduced water and air is required; when the water is saturated with salt, three quarters of the 15 air is driven out of the solution.

Further advantages will appear in the following description of my improved means.

This application is a continuation, in part, of 20 of my application Serial No. 574,149, filed Nov. 10, 1931, now matured into Patent No. 1,923,896, dated August 22, 1933.

Referring to the drawings, which illustrate, merely by way of example, suitable embodiments of my invention:— 25

Fig. 1 is a diagrammatic vertical section showing one form of embodiment.

Fig. 2 is a similar view of another form.

Fig. 3 is a similar view of another form.

Fig. 4 is a similar view of another form.

Fig. 5 is a similar view of another embodiment.

Fig. 6 is a similar view of another embodiment.

Fig. 7 is a fragmentary vertical section showing a different arrangement. 35

Fig. 8 is a diagrammatic view indicating the shape which the cavity will assume during the dissolving.

Similar numerals refer to similar parts through 40 out the several views.

The well, as shown in Fig. 1, is cased with 10" tube 1 through gravel into rock. An 8" casing 2 is cemented into lower part of shale roof and upper part of salt bed. A 6" casing 3 extends 45 to the top of the undercut, and a 3" tube 4 to bottom of the salt. Such an arrangement is adapted to undercut a rock salt bed, as for example, in a 1500 ft. well with 100 ft. of salt.

With the arrangement shown in Fig. 1, the 50 water, at pressure of about 200 pounds to the square inch, is pumped into the 3" tube or casing 10, passing into the cavity where it circulates and dissolves salt off the circumference of the cavity and flows upwards through the an- 55

nular space between the tubes 9 and 10, as par- with its bottom end at the top of desired under-

5 cut. To prevent attack of the salt above the end of the tube 9, air, of about 700 pounds per square inch pressure, is pumped into the annular space between tubes 8 and 9, forcing the water down until the air bubbles under the end of tube 9. This will maintain the water level at this level and an air cushion will fill the 10 space between the ripples on top of the brine as long as there is a surplus of air kept moving into the tube 9.

I have indicated in the drawings the colors red, blue, green and yellow, in accordance with the

15 official chart. The color red indicates air or other fluid medium for separating the solvent from the soluble; blue indicates water or other solvent; green represents sulphur water, and yellow indicates brine or solution.

20 In the modification shown in Fig. 2, the well is piped with a 3" tube 11 to the bottom of the salt, and a 6" tube 12 is packed off in the 8" tube 13 which is cemented in the rock. The 6" tube 12 may be stopped at the top of the salt or 25 extended down into it to top of the undercut as shown.

The well is operated by forcing water down the annular space between tubes 11 and 12, and brine out of tube 11. Air is forced in with the 30 water and entrained in the form of bubbles, which reduce in size by absorption and increase of pressure. The air is therefore compressed to the pressure of the water at the bottom of the well and holds back the liquid to required level.

35 Small holes 13 in tube 11, at level of top of undercut, allow surplus air to escape into the brine, thereby regulating the level of air which fills the space around the tubes to the underside of packer. This arrangement reduces the pressure of air needed to the pressure of the water at top of well instead of the bottom as in Fig. 1.

In accordance with the modification shown in Fig. 3, the 3" tube 14, reaching to the bottom 45 of the salt, is provided with a bell 15 which is either part of the 6" tube 16 or will slide down through it. This bell receives the surplus air at the level of the top of the undercut and transfers it, through small holes or passages 17, into the 50 3" tube 14.

The water is forced down through the annular space between the tubes 14 and 16 and out through holes or space 18 above the bell 15.

Air is forced through the crown of small tubes 55 19 into the water and is carried down entrained as small bubbles subject to increasing pressure.

The amount of air absorbed increases with the depth and pressure of the water. As the salt 60 dissolves, it drives out a portion of the air which has been absorbed. If a surplus of air, over the amount absorbed, any leakage and the volume required to fill the space around the tube up to the packer, is forced in, the surplus escapes under the bell and, entering the tube 14, helps to elevate the brine passing up this tube.

In accordance with the modification shown in Fig. 4, the 8" casing 20 is cemented into the rock and the top of the rock salt bed.

A 6" casing 21 is extended down nearly to the 70 level of the undercut.

A 3" tube 22 extends to the bottom of the salt. The connections of water and brine and air pipe are arranged so that the well can be operated either way, with brine or water in the 3" tube 22.

75 A 1" pipe 23 is suspended inside the 3" tube 22,

with its bottom end at the top of desired undercut. This 1" pipe 23 may be very readily moved up or down or changed in position, to regulate the level of the air cushion, and consequently the top level of the solvent, outside of the 3" tube 22.

The air which is forced into the water through the crown of small tubes 19 is carried down with the water, and the surplus fills the space between the tubes 20 and 21 to the top of the well.

This space between 20 and 21 is connected, 10 through a piping 23', to the 1" center pipe 23, and the surplus air passes out of this space, to and through the 1" center pipe 23 into the 3" pipe 22.

If this pipe 23 and piping 23' are wide open, 15 the level of the top of the water outside the 3" tube 22 will be enough below the end of the 1" pipe 23 to overcome the friction of the air passing up the annular space, through the piping and valves and down the 1" center pipe 23.

If a reducing valve 28, shown in the piping 23', is set to obstruct the air, the level of the air cushion will be lowered the amount of the differential pressure measured in feet of water.

With a 1500 ft. well with weak brine, 18 cu. ft. 25 of air per minute will maintain the level with very little surplus. When the brine is saturated, only 6 cu. ft. are required.

With this amount of air the friction in the tubing will be negligible and the level will be 30 very little below the end of the 1" pipe 23, when the reducing valve is wide open.

The above amounts are when using 20 cu. ft. of water=200 gal. per min.

In Fig. 4 are also shown air gages 25 and 26, 35 the mercury gage 27 and a reducing valve 28, the hand pump 29 and also a number of valves in the air line, the water line and the brine line, whereby the several flows and the direction of flow may be controlled. Also the center air pipe 23 may be 40 arranged for change of vertical position.

By the proper manipulation of these several instrumentalities, the level of the solvent may be regulated during the several stages as required.

This arrangement of well eliminates all packers, uses simple tubing without any connection between them at the bottom, and the regulation is all accomplished at the top of the well. The 50 level can be varied at will.

The air indicator 30, is suspended in the space between pipes 20 and 21. The bottom end being below the top of the undercut. The hand air pump 29 is operated to force air into the tube 30 until it bubbles under the bottom end. The difference in pressure indicated between gage 25 and gage 26, shows the distance between the water level and the bottom of the air indicator-pipe 30.

In Fig. 5, is shown a structure similar to that shown in Fig. 4, somewhat simplified. It also 60 illustrates the form which the cavity assumes during dissolving. In addition to the parts, as numbered in Fig. 4, 32 indicates the inlet for fresh water, 33 the air inlet pipe, 34 the discharge pipe for brine.

In accordance with the arrangement shown in Fig. 6 the annular bell 36 surrounds the brine tube 22, with its lower margin approximate the top of the desired undercut. This bell is supported upon a number of air pipes 37 and may be raised from time to time as the dissolving proceeds upwardly in stages, without changing the center brine pipe 22. These air pipes 37 are adapted to deliver the air to central pipe 23. An injector 38 is shown in this figure, which is adapted to utilize the air un- 75

der pressure delivered through pipes 37 from bell 36, in introducing air with the water at the top of tube 21.

In accordance with the arrangement shown in

- 5 Fig. 7, a bell 39 is provided to surround the brine tube 22. The bottom of the bell is approximate the top of the undercut, and the air coming down with the water between casings 21 and 22 separates from the water and passes under said lower 10 margin of the bell. A plurality of small tubes 40 are connected to the brine tube 22 as at 41. These tubes project upwardly in the bell and are open at the top so that, as the bell fills with air under pressure, the surplus air will enter the brine tube 22 through these tubes 40 without danger of carrying fresh water therewith. The position of the lower margin of the bell will define the level of the water in the mine cavity.

Fig. 8 indicates the approximate shape of the 20 roof of the cavity 42 as the dissolving progresses upwardly. The arched formation of the roof of this cavity makes it possible to dissolve almost the entire bed of salt before the roof caves in.

By soluble is meant salt or other mineral capable 25 of being dissolved.

By solvent is meant any fluid medium capable of dissolving the soluble.

By non-solvent is meant any fluid medium which will not dissolve the soluble.

30 What I claim is:—

1. In a system for mining a soluble by introducing a solvent into a cavity formed in the soluble and discharging the resulting solution, means for controlling and changing as required 35 the level of the solvent in the cavity, comprising a pipe for introducing the solvent, a pipe for discharging the solution, means for introducing compressed air into said cavity above the solvent, an adjustable air pipe discharging into the solution pipe at a point near the level of the solvent in said cavity, and means for delivering air from the cavity to said air pipe.

2. In a system for mining a soluble by introducing a solvent into a cavity formed in the 40 soluble and discharging the resulting solution, means for controlling and changing as required the level of the solvent in the cavity, comprising a pipe for introducing the solvent, a pipe for discharging the solution, means for introducing 45 compressed air into said cavity above the solvent, an air pipe discharging into the solution pipe at a point near the level of the solvent in said cavity, a piping connecting the air space in the cavity with said air pipe, said connecting piping provided with a reducing valve.

3. In a system for mining a soluble by introducing a solvent into a cavity formed in the soluble and discharging the resulting solution, means for controlling and changing as required 50 the level of the solvent in the cavity, comprising a pipe for introducing the solvent, a pipe for dis-

charging the solution, means for introducing compressed air into said cavity above the solvent, an adjustable air pipe discharging into the solution pipe at a point near the level of the solvent in said cavity, a piping connecting the air space in the cavity with said air pipe, provided with a 5 reducing valve, the adjustable air pipe and the reducing valve adapted to be used independently and also in cooperation in controlling the level of the solvent in the cavity.

4. In a system for mining a soluble by introducing a solvent into a cavity formed in the soluble and discharging the resulting solution, means for controlling and changing as required the level of the solvent in the cavity, comprising 10 a pipe for introducing the solvent, a pipe for discharging the solution, an annular bell surrounding the solution pipe having the margin of its open end approximately at the level of the solvent, an adjustable air pipe discharging into 15 the solution pipe at a point near the level of the solvent in the cavity and means for delivering air from the bell to the air pipe.

5. In a system for mining a soluble by introducing a solvent into a cavity formed in the 20 soluble and discharging the resulting solution, means for controlling and changing as required the level of the solvent in the cavity, comprising a pipe for introducing the solvent, a pipe 25 for discharging the solution, an adjustable bell 30 surrounding the solution pipe having the margin of its open end approximately at the level of the solvent, and an air pipe discharging from the bell to the solution pipe.

6. In the operation of dissolving a soluble by introducing a solvent into a cavity made in the soluble, introducing also a non-solvent for controlling the action of the solvent, and discharging the solution from said cavity, the method which consists in controlling the top level of the 35 solvent first to secure dissolving outwardly in a horizontal plane close to the bottom of the cavity, in order to undercut the mass of soluble, and then to permit the dissolving in stages upwardly until substantially the entire mass of 40 soluble is dissolved.

7. In the operation of dissolving a soluble by introducing a solvent into a cavity formed in the soluble, introducing also a non-solvent for controlling the action of the solvent, and discharging 50 the solution from the bottom of the cavity, the method which consists in maintaining the top level of the solvent in a plane close to the bottom of the cavity until the dissolving has proceeded to the maximum extent of the undercut, and then permitting dissolving, in progressive stages upwardly, eventually to form the entire roof of the cavity dome-shaped, when the dissolving of approximately the entire deposit of 55 soluble has been completed.
